UNITED STATES PATENT OFFICE.

WILLIAM L. POPE, OF HUNTERSVILLE, NORTH CAROLINA.

TRACTOR.

1,397,015.

Specification of Letters Patent. Patented Nov. 15, 1921.

Application filed September 7, 1920. Serial No. 408,566.

To all whom it may concern:

Be it known that I, WILLIAM L. POPE, a citizen of the United States, residing at Huntersville, in the county of Mecklenburg 5 and State of North Carolina, have invented a new and useful Tractor, of which the following is a specification.

This invention relates to tractors, one of its objects being to provide a machine of 10 this character having means for transmitting motion from the engine to all of the supporting wheels, it being possible to shift one of the wheels bodily for the purpose of steering the vehicle without, however, interfering with the drive to said wheel.

A further object is to provide a tractor having means whereby agricultural implements, while connected, can be raised and lowered so as to engage the soil at the proper 20 depth.

With the foregoing and other objects in view, which will appear as the description proceeds, the invention resides in the combination and arrangement of parts and in 25 the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a plan view of the tractor.

Fig. 2 is a bottom plan view thereof.

Fig. 3 is an enlarged section on line 3—3,

Fig. 1.

Fig. 4 is an enlarged section on line 4—4,

Fig. 1.

Fig. 5 is an enlarged section on line 5—5,

Fig. 1.

Fig. 6 is an enlarged section on line 6—6,

Fig. 1.

Referring to the figures by characters of 45 reference 1 designates the frame of the tractor one side of which is preferably bulged at the center, as shown at 2 while the other side is preferably straight with its front end 3 projecting laterally and the rear end provided with an inwardly projecting portion 4. To the frame 1 is secured a suitable platform 5 carrying the engine 6 which can be of any preferred construction and also carrying the seat 7 to be occupied by the driver.

Secured to one side portion of the tractor adjacent the inwardly projecting portion 4 is

a bracket 8 having a spindle 9 extending therefrom and laterally beyond the frame of the tractor. On this spindle is journaled a supporting wheel 10 of any desired construction and provided with an internal gear 11. This gear meshes with a small drive gear 12 secured to a shaft 13 which is journaled in a bearing 14 provided therefor on the tractor frame. A worm gear 15 is secured to the shaft 13 and meshes with a worm 16 carried by the upper end of a vertical shaft 17 which is suitably journaled within the platform of the tractor and within the bracket 8 and is provided at its lower 70 end with a worm gear 18 arranged under the platform 5.

Another bracket 19 is secured to the bulged side portion 2 of the tractor frame and has a spindle 20 extending laterally beyond the tractor frame. A supporting wheel 21 is journaled on this spindle and has an internal gear 22. This gear constantly meshes with a small driving gear 23 which is keyed on a shaft 24 mounted in a suitable 80 bearing 25 on the bracket 19. The shaft 24 is adapted to slide within the gear 23 and has a head 26 seated within a recess 27 in said gear. A spring 28 is housed in the recess in gear 23 and comes against the head 26. A clutch member 29 is mounted on and rotates with the shaft 24 although said shaft is capable of sliding therein. A worm wheel 30 is loosely mounted on the shaft 24 and is with clutch face 31 adapted to engage the 90 clutch member 29. Thus it will be seen that the spring 28 serves to hold the clutch face 31 normally pressed against the clutch member 29 so that when the worm wheel 30 is rotated under ordinary conditions the clutch member 29 and the gear 23 will also be rotated. When, however, the rotation of the worm wheel 30 is subjected to excessive resistance, said wheel will be free to rotate independently of the clutch member 29, the 100 face 31 slipping over said clutch member 29 against the action of the spring 28.

A worm 32 engages the worm wheel 30 and is provided at the upper end with a vertical shaft 33 extending downwardly 105 through the bracket 19 and platform 5. To the lower end of this shaft is secured a worm wheel 34.

Pivotedly mounted on the tractor frame where it extends laterally, as indicated at 3, 110 is a bracket 35, this bracket being adapted to swing about a tubular pivot member 36

as shown in Fig. 4. On the bracket is arranged a bearing 37 and extending laterally from the bracket is a spindle 38 on which is journaled a supporting wheel 39. This wheel has an internal gear 40 constantly engaged by a small gear 41 secured to a shaft 42 journaled in the bearing 37. A worm wheel 43 is secured to the shaft 42 and is engaged by a worm 44 secured to the upper portion of a vertical shaft 45. This shaft is journaled within the tubular pivot 36 and is provided, at its lower end, with a worm wheel 46.

The engine 6 drives a sprocket 47 adapted to transmit motion through a chain 48 to a sprocket 49 secured to a longitudinal shaft 50. This shaft is journaled in suitable bearings 51 on the bottom of the tractor platform and has worms 52 at the ends thereof for engaging the respective worm wheels 18 and 46. A bevel-gear 53 is secured to the shaft 50 and meshes with another bevel-gear 54 secured to a transverse shaft 55. This shaft is journaled in suitable bearings 56 on the bottom of the tractor and has a worm 57 which meshes with the worm wheel 34. Thus it will be seen that when the engine is operating, motion will be transmitted therefrom to the shaft 50 which, in turn, will drive the various worms 52 and 57 so that the worm wheels 18, 34 and 46 will all be actuated and the various supporting wheels will be driven at a slow speed.

35 The bracket 35 has its inner end concentric with the pivot thereof and provided with teeth as indicated at 58. These teeth are adapted to be engaged by a worm 59 secured to a shaft 60 journaled on the tractor platform. A bevel-gear 61 is secured to the shaft 60 and meshes with a bevel-gear 62 secured to a steering post 63. The steering wheel 64 is secured to this post and is located within convenient reach of the occupant of the seat 7. Thus it will be seen that by manipulating the wheel 64 the bracket 35 can be swung about its pivot so as to shift the wheel 39 and steer the tractor in a forward or backward movement. This 50 steering will in no way interfere with the transmission of motion to the wheel 39, however.

The inwardly projecting portion of the tractor frame indicated at 4 and in fact any 55 other portion of the side of the tractor can be provided with suitable means for adjustably holding ground engaging elements.

Each of these means, which have been indicated generally at 65 includes a guide bracket 66 secured to and extending laterally from the frame. In the bracket is slidably mounted a standard 67 having any suitable means such as indicated at 68 for attaching an implement to the standard. The upper end of the standard is provided 65 with teeth 69 adapted to be engaged by a worm 70 journaled on the tractor and which can be rotated by means of a hand wheel 71. Thus it will be seen that the standard 67 can be easily and minutely adjusted upwardly or downwardly to bring into proper relation to the surface of the soil the implement attached to the standard 67.

A suitable clevis or other form of attaching means indicated generally at 72 can 75 be provided for connecting various forms of agricultural implements to the tractor.

What is claimed is:

1. In a tractor the combination with 80 supporting wheels and means under the control of the driver for bodily shifting one of the wheels to steer the tractor, of a longitudinal shaft, a transverse shaft driven thereby, a motor for actuating the longitudinal shaft, a plurality of vertical shafts, means for transmitting motion thereto from the longitudinal and transverse shafts respectively, gears carried by the supporting wheels, drive gears meshing therewith, and means for transmitting motion to the drive 90 gears from the respective vertical shafts.

2. In a tractor the combination with a frame, a supporting wheel connected to the central portion at one side thereof, and non-aligning supporting wheels connected to the 95 end portions of the other side thereof, of means under the control of the driver for bodily moving one of the last named wheels to steer the tractor, an engine driven longitudinal shaft, a transverse shaft receiving motion therefrom, a vertical shaft adjacent each of the supporting wheels, means for transmitting motion to the vertical shafts from the respective longitudinal and transverse shafts, and means for transmitting 100 motion from the vertical shafts to the supporting wheels.

In testimony that I claim the foregoing as my own, I have hereto affixed my signature in the presence of two witnesses.

WILLIAM L. POPE.

Witnesses:

JOHN L. POPE,
J. McALEXANDER.
